Primary Examiner—Ruth McInroy**CLAIM**

The ornamental design for a grill, as shown and described.

DESCRIPTION

FIG. 1 is a left, front perspective view of a grill showing our new design;

FIG. 2 is a right, front perspective view thereof;

FIG. 3 is a front view of FIG. 2;

FIG. 4 is a rear view of FIG. 2;

FIG. 5 is a left side elevational view of FIG. 2;

FIG. 6 is a right side elevational view of FIG. 2;

FIG. 7 is a top view of FIG. 2; and,

FIG. 8 is a bottom view of FIG. 2.

The details shown in broken lines form no part of the claimed design.
